UNITED STATES PATENT OFFICE.

HENRY G. RYDHOLM, OF SAUK CENTER, MINNESOTA.

DRIER FOR PHOTOGRAPHIC PRINTS.

1,187,102.

Specification of Letters Patent. Patented June 13, 1916.

Application filed November 18, 1914. Serial No. 872,732.

To all whom it may concern:

Be it known that I, HENRY G. RYDHOLM, a citizen of the United States, residing at Sauk Center, in the county of Stearns and 5 State of Minnesota, have invented certain new and useful Improvements in Driers for Photographic Prints, of which the following is a specification.

My invention relates to driers for photographic prints and has for its object to provide a simple and efficient apparatus for use in a photographic studio whereby a roll of wet print may be subjected to uniform currents of heated air for drying purposes, 10 said device at the same time providing means for withdrawing the heat from the room so that the same may be used with comfort and satisfaction in warm weather.

The full objects and advantages of my invention will appear in connection with the detailed description thereof and are particularly pointed out in the claims.

In the drawings, illustrating the application of my invention in one form, Figure 25 1 is an elevation view of the complete drier. Fig. 2 is a sectional elevation of a portion of the parts shown in Fig. 1 on a larger scale and taken on line 2—2 of Fig. 1. Fig. 3 is a top plan view with the cover removed 30 and some of the parts broken away.

As illustrated, I provide an outer cylinder 10 secured to legs 11 by which the same is held spaced from the floor a proper distance, a table 12 providing a support for a heater 35 13, such as an oil or gas burner. Within cylinder 10, and held in proper relation thereto by means of securing members 14, is the drier cylinder proper 15. The cylinder 10 has its lower outwardly-rolled edge 40 16 at a point somewhat lower than the outwardly-rolled edge 17 of cylinder 15; and between the cylinder walls is an annular space 18. Secured to inner cylinder 15 at a point suitably raised above 45 the lower rolled edge 17 thereof by crossed brace bars 42 is a partition or dia- phragm 19, which is formed of imperforate material, preferably sheet metal, ex- cepting for a series of semicircular apertures 50 20 between the peripheral edge of said dia- phragm and the inner cylinder wall of cyl- 55 inder 15. There does not need to be any set number of said apertures 20, but in practice these may conveniently be fixed at four, so that there will be four such open spaces 20 and four intervening closed por-

tions of the diaphragm adjacent the cylindrical wall; all as clearly shown in Fig. 3. Held properly spaced above the diaphragm 19 secured to cylinder 15 by crossed brace 60 bars 43 is a second diaphragm 21 having an upper covering 22 of asbestos or other suitable insulating material. The diaphragm 21 is likewise provided with a series of peripheral apertures 23 similar to apertures 20 65 and staggered in respect thereto, so that apertures 20 open upon an imperforate portion of the diaphragm 21. The diaphragm 21 also has a series of smaller circular apertures 24 at the central part thereof. A cover 25 70 fits over the top of the outside cylinder and closes the same from the air of the room. The pipe 26 connects with the inner cylinder 15, while another pipe 27 connects with the outer cylinder 10, these pipes uniting 75 in a common pipe 28 which may be connected with a chimney flue.

In operation the roll of wet print is placed on end upon the insulated surface 22 of the upper diaphragm 21 and the cover 80 25 closed over the apparatus. The flame of the burner 13 strikes upon the bottom of the imperforate diaphragm 19 and spreads out over said bottom, the hot gases passing through the peripheral apertures 20. After 85 these gases pass through apertures 20 they strike upon the imperforate portions of the diaphragm 21 and spread over the surface thereof, finally passing through the peripheral apertures 23 and the central apertures 90 24, where said gases may pass through all parts of the print roll within the cylinder 15, finally escaping through the pipe 26. Any gases or heated air which do not pass within and through the cylinder 15 will 95 enter the annular passageway between the walls of cylinders 15 and 10 and be carried to pipe 28 through pipe 27. This keeps the outer wall of cylinder 10 comparatively cool and perfects the escape of heat from the 100 drier into the studio room, and also carries off all the gases of the burner. If, however, it were desired to throw said gases into the room for heating the same, or for any other purpose, dampers 29 in the pipes 26 and 105 27 might close said pipes and the cover 25 be removed, in which case all the gases and surplus heat of the burner would pass into the room. Cylinder 15 may be provided with a cover 45 which in conjunction with 110 the damper 29 in pipe 26 can prevent the escape of gas from said cylinder and so

produce a greater degree of temperature within said cylinder.

I claim:

1. A drier for photographic print rolls, comprising a pair of concentric cylinders with an annular space between the walls thereof, means for supporting said cylinders in vertical position, means for supporting a burner below said cylinders, means for withdrawing the gases of combustion from both of said cylinders, means for supporting the photographic print so as to permit the heated air and gases from the burner to pass through the print, and means for first deflecting said gases before they enter said cylinders so that they will be spread and of uniform temperature before passing through the roll of print.
2. A drier for photographic print rolls, comprising a pair of concentric cylinders with an annular space between the walls thereof, means for supporting said cylinders in vertical position, means for supporting a burner below said cylinders, means for withdrawing the gases of combustion from both of said cylinders, an insulated support for the photographic print having openings therein such as to permit distribution of the heated air and gases from the burner to all parts of the print, and means for first deflecting said gases before they enter said cylinders so that they will be spread and of uniform temperature before passing through said openings.
3. A drier for photographic print rolls, comprising a pair of concentric cylinders with an annular space between the walls thereof, means for supporting said cylinders in vertical position and for supporting

a burner below the same, means for withdrawing the gases of combustion from both of said cylinders, and a pair of horizontal partitions spaced from one another in and adjacent the bottom of the inner cylinder, said partitions being formed with openings adjacent the junction of the partitions with the cylinder wall, said openings being in staggered relation so that the heated air and gases from the burner will be deflected and spread and of uniform temperature before passing through the inner partition.

4. A drier for photographic print rolls, comprising a pair of concentric cylinders with an annular space between the walls thereof, means for supporting said cylinders in vertical position and for supporting a burner below the same, means for withdrawing the gases of combustion from both of said cylinders, and a pair of horizontal partitions spaced from one another in and adjacent the bottom of the inner cylinder, said partitions being formed with openings adjacent the junction of the partitions with the cylinder wall, said openings being in staggered relation so that the heated air and gases from the burner will be deflected and spread and of uniform temperature before passing through the inner partition, said inner partition being provided with interior apertures and having an insulating covering for the reception of the roll of print.

In testimony whereof I affix my signature in presence of two witnesses.

HENRY G. RYDHOLM.
